JOHN KINCAID, OF VANCOUVER, CANADA.

ROLLER-BEARING.

SPECIFICATION forming part of Letters Patent No. 730,773, dated June 9, 1903.

Application filed January 12, 1903. Serial No. 138,708. (No model.)

To all whom it may concern:

Be it known that I, JOHN KINCAID, a citizen of the Dominion of Canada, residing at Vancouver, in the Province of British Columbia, Canada, have invented a new and useful Improvement in Roller-Bearings, of which the following is a specification.

My invention relates to the application of roller-bearings to the requirements of relatively heavy loads, such as are incidental to ordinary steam-engine practice; and it consists, primarily, in the particular construction of the rollers themselves and in its complete form of the means by which their alignment is preserved and their distance apart maintained. I have realized that the principal objection hitherto to the use of rollers in this connection has been in the difficulty of providing a roller that should be free from the possibility of cross-winding and at the same time not liable to objectionable warping in the process of hardening, either of which faults impair very seriously their efficiency as rollers. I therefore do not attempt to provide a roller of any considerable length, but place a series of short ones of V shape in radial cross-section side by side on spindles which are maintained the proper distance apart by an exterior framework into which the spindles are secured, the rolling surfaces of the moving parts of the machine in which it is desired to introduce them being provided with parallel grooves in the line of motion adapted in cross-section to the V form of the rollers.

My invention is fully described in the following specification and illustrated in the drawings which accompany it, Figure 1 being a side elevation of an engine cross-head and guide-bars having my roller-bearings applied to the lower or foregoing bar; Fig. 2, a cross-section of the roller-bearing of the same; Fig. 3, a side elevation showing the application of my rollers to a crank-pin bearing, and Fig. 4 a cross-section of the same.

In Figs. 1 and 2, illustrating the application of my roller-bearings to an engine cross-head, the cross-head is represented by *c*, the guide-bar by *b*, and the intermediate rollers by *b*. The particular form of these rollers is clearly illustrated in Fig. 2, the opposite sides

being somewhat as drawn and the slope of the sides such as will preclude the possibility of any side binding due to the wedging tendency. Each roller is bored, and they are arranged side by side on spindles 5 in such number as to suit the requirements of the pressure between the surfaces, the ends of the spindles being secured in side members 6 of a rectangular frame, by means of which the longitudinal spacing of the rollers is maintained. The surfaces of both the cross-head and the guide-bar with which the rollers engage are provided with a series of longitudinal grooves $c^2 b^2$, corresponding to the number of rollers on each spindle and in shape accurately fitted to the radial cross-section of the rollers. These grooves will keep the rollers laterally in place, and the combination of rollers and grooves will preserve the alignment of the moving parts. I prefer that the bottom of the grooves have a deepened parallel portion, as at 4, so as to insure the rollers bearing only on the inclined sides and not on the cylindrical periphery. With the application of strain consequent on this construction of rollers and grooves it is obvious that the roller is individually a particularly strong one and one that can be hardened or tempered without risk of serious distortion, that having a short rolling base it will not be subject to the evil of cross-winding, and its ample lateral support in the grooves will preclude the possibility of it turning over sidewise, as a roller of such shortness in relation to diameter would otherwise be very liable to do.

Another advantage of my system is that although I may use a roller of considerable diameter I do not require to similarly increase the distance from center of cross-head pin to outside of bar, as the ridges between the grooves will serve to maintain to a considerable extent the strength of the respective parts.

In the application of my system of roller construction to the requirements of a crank-pin, eccentric, or ordinary journal-bearing there is little difference in the construction other than that necessitated by the cylindrical form of the rolling-surfaces.

Figs. 3 and 4 illustrate in front elevation

and cross-section the application to a crank-pin bearing as typical of the class, the connecting-rod end being represented by r and the crank-pin by p , the rollers being, as before, indicated by 3 and the grooves by r^2 p^2 .

The supports of the roller-carrying frame may be rings, as 8 in Fig. 4, and may be made either in one piece, as drawn, or for convenience of removal in two or more segments; 10 but for the front support of an end bearing, such as a crank-pin, may be a disk, as 7 in Figs. 3 and 4, covering the end of the pin and tending to exclude dust. The spindles 5 may be screwed or riveted in the support-frames 15 or secured in any appropriate manner.

I am aware that in the construction of roller-bearings spindles and frames have been previously used to maintain the spacing of the rollers and that conical sides have been used 20 to prevent lateral movement; but I believe no attempt has heretofore been made to provide a bearing, such as I have described, in which the entire pressure on the bearing has been borne on the conical sides of a series of 25 short rollers so supported with spindle and frames.

I therefore declare that what I claim as

new, and desire to be protected in by Letters Patent, is—

A roller-bearing for the purposes described, 30 comprising a pair of opposing surfaces said surfaces having a series of opposing V-shaped grooves, the grooves of one surface being disposed in alinement with the grooves of the other surface, each surface having supplemental grooves at the bottom of the V-shaped 35 grooves; a framework having crossed spindles, a series of double cone-rollers upon each cross-spindle, said rollers including a cylindrical portion at the intersection of the cone-surfaces, said cylindrical portion being of a width equal that of the supplemental grooves in the opposing surfaces, the sides of each roller being adapted to fit in the opposing grooves and to bear on the V-shaped surfaces 40 thereof, substantially as shown and described.

In testimony whereof I have signed my name to this specification in the presence of two subscribing witnesses.

JOHN KINCAID.
